Specification of Letters Patent.

Patented Feb. 6, 1912.

Original application filed June 11, 1909, Serial No. 501,462. Divided and this application filed November 19, 1909. Serial No. 528,943.

To all whom it may concern:

Be it known that we, GEORGE S. SAVIGNAC and CHARLES E. MYERS, both citizens of the United States, and residents of the city of St. Louis and State of Missouri, have invented a certain new and useful Improvement in Take-Ups and Thread-Measurers for Sewing-Machines, of which the following is a specification.

- 10 The subject matter of the present invention is divided out of an application for Letters Patent for an improvement in sewing machines, Serial No. 501,462, filed by us on June 11, 1909.
- 15 The present invention relates to take-ups and thread-measuring devices for sewing machines and more particularly those used for sewing leather and the like.

The principal objects of the invention are 20 to produce a simple and effective device which will readily take up the thread to set or complete the stitch, to provide for adjusting said device to measure off the proper amount of thread according to the length of 25 stitch and thickness of the work, and to attain certain other advantages hereinafter more fully appearing.

The invention consists in the parts and 30 in the arrangements and combinations of parts hereinafter described and claimed.

In the accompanying drawings which 35 form part of this specification and wherein like symbols refer to like parts wherever they occur, Figure 1 is a front elevation of 40 a sewing machine embodying our invention; Fig. 2 is a side elevation of a portion of the sewing machine showing the position of the take up arm at the two limits of its movement; and, Fig. 3 is a view similar to Fig. 40 2 showing the take-up in the act of pulling the thread to set the stitch.

The general construction and arrangement of the sewing machine is fully set forth in the application for Letters Patent, 45 Serial No. 501,462, hereinbefore referred to. The machine comprises a suitable base 1 which may be mounted on any suitable table or stand, not shown. On the base 1 is a suitable standard 2 in the lower portion of 50 which is journaled a driving shaft 3. On the end of the shaft is a pinion 4. This pinion meshes with a gear-wheel 5. The gear-wheel 5 is mounted upon a countershaft 6

which is journaled in the standard 2 above the driving shaft 3. Fixedly secured to the gear wheel 5 or on the shaft 6 is a cam disk or member 7. This cam disk or member 7 is provided in its front face with two continuous cam grooves 8, 9, whose functions will hereinafter more fully appear. 60

Mounted on the base 1 close to the front face of the cam disk 7 is a vertically disposed guide frame or column guides 10, on which is slidably mounted a block or member 11. This block is preferably provided with grooves in its side edges which slidably fit vertically disposed ribs 12 provided therefor on the inner side face of the guide frame or column guides 10. The upper ends of the column guides are connected by a cross-bar or member 13 which is secured by bolts or other suitable securing devices 14. Projecting rearwardly from the block 11 is a stud or roller 15 which is adapted to fit in the cam groove 8 of the disk 7, whereby a 70 vertically reciprocating motion is imparted to said block when the cam disk 7 is rotated.

Mounted on the forward portion of the base 1 is a standard 16 which is preferably stiffened by suitable marginal and intermediate ribs or flanges 17. The upper portion of the standard 16 is formed into a circular casing or housing 18 having flattened side walls; and the housing is preferably 80 divided, or one of its side walls is made removable so that access may be conveniently gained to the interior of the housing. 85

Journaled transversely of the housing is a rock-shaft 19 on which is fixedly mounted a segment gear 20 which is provided with 90 two oppositely disposed segmental extensions or wings 21, 22.

Journalled on a transverse shaft 23 in the rear portion of the housing is a segment gear 24 which meshes with said segment gear 95 20. The segment gear 24 is provided with a lever-extension or rock-arm 25 which is pivotally connected to one end of a link or bar 26 whose opposite end is pivotally mounted between a pair of ears or lugs 100 located on the front face of the vertically reciprocating member 11, whereby, when said member is reciprocated vertically, the segment gear 20 and the rock-shaft 19 upon which it is fixed, are rocked or oscillated. 105

The upper front portion of the housing

18 is cut away to provide a space for a work table or shelf. The work table or shelf preferably comprises a flat plate 28 having a down turned portion 29 which is secured by screws 30 or by any other desirable means to the side wall of the housing. This plate 28 is provided with a laterally elongated slot, not shown, through which the awl and needle work.

19 An awl 31 is pivotally mounted on the segmental extension 21 of the segment gear 20. The awl is arranged to coöperate with certain devices within the casing or housing 18 so as to be shifted or oscillated laterally on its pivot when it is reciprocated by the oscillation of the segment gear 20. A needle 32 is mounted on the segmental-extension 22 of the segment gear 20. Both the needle and the awl are curved on the same radius from the center of the rock-shaft 19. The needle is provided with an eye near its pointed end through which the needle thread A is passed so that when the needle moves through the work, it carries a bight or loop of the thread 25 therethrough.

30 In the operation of the machine, the awl upon its upward stroke pierces or punctures the work and during this upward movement of the awl, it is shifted laterally, thereby feeding the work a predetermined distance into position to bring the puncture in the work into the path of the needle. As the awl backs out of the work, upon its reverse or downward stroke, the needle follows 35 through the puncture. This operation is successively repeated for the succeeding stitches. As above stated, the needle 32 carries a loop of the thread A through the work. When the needle starts to back out 40 of the work, the loop is opened. At the instant the loop is opened, a locking loop carrier 33 carries a loop of the locking loop thread B through the first mentioned needle thread loop. This locking loop carrier is 45 arranged to reciprocate horizontally and it is actuated to quickly return to normal position and thereby leaving the locking loop in the needle loop. Immediately after this actuation, the take up device is actuated to 50 pull the needle thread A and thereby interlock the two loops and draw the same into the work to set or complete the stitch. As shown in the drawing, the locking loop carrier is actuated by an arm 34 on a rock shaft 55 having a second arm 36 thereon. The arm 36 is provided with a stud or roller 37 which fits in the groove 9 in the cam disk 7, whereby an intermittent rocking motion is 60 imparted to the shaft and the arms thereon. The take up device for the needle thread 65 comprises an arm 38 which is fixed tightly on the end portion of the rock shaft 19 outside of the housing. This arm 38 is set with respect to the segmental extensions 21, 22, of the segment gear 20 so that it is in its

70 lowermost position when the needle and the awl are in their uppermost positions. The arm 38 is provided near its outer end with a circular portion 39 having a curved marginal flange or rib 40 on its outer side. The inner side of the flange or rib 40 is curved eccentrically with respect to the center of the circular portion 39 of said arm 38. Pivotally mounted on a stud 41 which is located at the center of the circular portion 39, is a cam disk 42 whose high side or portion which coöperates with the eccentric side of the rib 40 is preferably serrated or scalloped as at 43. Pivotally mounted on the outer end of the arm 38 is a lever-arm 44 which has a slot 45 therein which coöperates with a stud 46 on the cam disk 42. The free end of the lever arm 44 is for convenience turned at an angle as at 47 and it is rounded or pointed at its end so as to coöperate with a resilient latch member 48. This latch member is mounted on an arcuate extension 49 of a bracket 50 which is mounted on the top of the casing 18. The bracket extension 49 is 80 preferably suspended laterally from the casing so as to be in convenient position relative to the arm 38. On the free end of the latch member 48 is provided a lug 51 having a tapered or beveled side cam face 51 and a curved or grooved top cam face 52. The opposite end of the latch member is secured to the bracket extension by a screw or rivet 53 and it is additionally supported by a pin 54 upon which its intermediate free portion slidably rests. 90

100 Assuming the parts just described to be in the position shown in Fig. 2; when the arm 38 is swung upwardly, the end portion 47 of the lever arm 44 rides over the cam face 51 on the lug 51 on the end of the resilient latch member 48, thereby pressing said member inwardly until said lever arm has passed free of the lug. When the arm 38 swings downwardly on its return stroke, the end portion 47 of the lever-arm 44 contacts with and rides over the grooved cam portion 52 of the latch member, whereby said lever arm 44 is shifted and, owing to its slot-and-pin connection with the cam disk 42, the disk is turned until its high side contacts with the inner face of the curved rib 40, as shown in Fig. 3. As the arm 38 continues its downward movement a projection 55 on the cam disk 42 contacts with a projection 56 on the bracket extension 49 whereby the cam disk 42 is turned and restored to inoperative position, the lever 44, of course, being also restored therewith to the position shown in Fig. 2. The projection 56 is 110 preferably provided on a slotted plate 57 which is secured in adjusted position on the bracket extension 49 by a screw 58 or other suitable securing device. By adjusting the projection 56 to different positions peripherally of the arcuate extension 49, the cam 115

disk 42 may be made to move out of contact with the rib 40 at different intervals from the tripping lug 51* on the end of the latch member 48, and thereby the amount of the 5 needle thread taken up in the stitch may be varied, as hereinafter more fully described.

In order to releasably hold the cam disk 42 in open position, as shown in Fig. 2, a 10 spring-latch or retainer 59 is provided on the circular portion 39 of the take-up arm 38. This retainer preferably comprises a curved leaf-spring which is provided with a V-shaped end portion which is adapted to fit in front of a shoulder 60 provided on the 15 cam disk 42 adjacent to the projection 55. By this arrangement, the angular end portion of the spring will ride up over the shoulder when the cam disk is forcibly turned; and it will snap back into place in 20 front of the shoulder when the cam disk is restored to open position, yet the resiliency of the spring is sufficient to hold the disk against accidental movement.

In the operation of the thread-measuring 25 and take-up device just described, the needle thread is taken from some conveniently arranged source of supply, preferably, from a spool holder 61 mounted or supported beneath the base 1 of the machine. The thread 30 is carried through an opening 62 in the base and thence through an ordinary tension device 63 which may be conveniently mounted on the base or guide-frame 10, as shown. It is then carried under a suitable guide piece 35 or clip 64 on the lower end portion of the rib 40 on the take up arm 38, thence between the inner side of said rib and the cam disk 42, thence through a slotted guide-opening 65 in the upper end portion of the rib 40, 40 thence over a grooved idler or pulley 66 on the top of the casing 18, and thence over the outer side of the curved needle 32 and through the eye of the needle. It is preferable, however, to pass the thread through a 45 waxing or treating device 67 which is preferably located between the idler 66 and the needle 32 as will be more fully set forth in another application to be divided out of our application, Serial No. 501,462, hereinbefore set forth. When the needle 32 moves 50 downwardly, it carries a bight or loop of the thread A with it. The end of the thread or portion thereof which is secured in the preceding stitch is, of course, tightly held, and, therefore, the thread from the supply 55 spool is pulled through the tension device and the take up device and over the idler or pulley. It is noted, also, that the take up arm moves upwardly simultaneously with 60 the downward movement of the needle. The tripping or latch member is so located that immediately, or shortly after, the take up arm starts on its return or downward stroke, the lever-arm 44 is actuated and the 65 cam disk 42 binds the thread against the rib

40 on the take up arm. The thread is then pulled until the cam disk 42 is released from the thread by the projection 55 on said disk contacting with the projection 56 on the bracket extension 49. It is during this pulling action on the thread by said take up device that the stitch hereinbefore described is tightened or set. The length of the thread used to form and set the stitch is controlled by the distance between the projection 56 and the tripping lug 51* on the member 48; and as hereinbefore stated, said projection 56 may be adjusted at will with relation to said grooved cam 52 in order to measure the proper length of thread to suit different thicknesses of work or lengths of stitches. The locking-loop thread, B is preferably supplied from a spool mounted on a holder 68 located conveniently beneath the base 1. The supply of thread-waxing or treating 80 material is also preferably located beneath the base 1. A supporting bracket 69 is therefore, secured to the under side of the base. It has two oppositely disposed arms 70, 71, on which the spool holders 61, 68 are 85 respectively mounted. It also has a depending portion 72 to which the supply tank or reservoir 73 is secured. The thread B is passed up through a hole in the base 1 in a manner similar to the thread A. It is thence passed through a guide member 74 depending within a receptacle 75 which is adapted to contain the waxing or treating material 90 for the thread.

Obviously, the device admits of considerable modification without departing from our invention. Therefore, we do not wish to be limited to the specific construction and arrangement shown.

What we claim as our invention and desire 105 to secure by Letters Patent is:

1. In a sewing machine, the combination with a stitch-forming mechanism, of a combined thread-measuring and take-up device comprising a rock-arm, a thread-guide thereon, an eccentric disk pivotally mounted on said rock-arm with its peripheral face in co-operative relation to said thread-guide and adapted to clamp the thread therebetween, means for automatically throwing said eccentric disk into effective position while the rock-arm is moving in the direction to pull the thread and set the stitch, said means comprising a lever on the rock-arm and a co-operating tripping device on a stationary 110 part of the machine, and means for throwing said eccentric disk into ineffective position at a predetermined time during the pulling stroke of said rock-arm.

2. In a sewing machine, the combination 125 with a stitch-forming mechanism, of a combined thread-measuring and take-up device comprising a rock-arm, a thread-guide thereon, a disk pivotally mounted on said rock-arm and having a peripheral cam face in co- 130

operative relation to said thread-guide and adapted to clamp the thread therebetween, means for automatically throwing said disk into effective position while the rock-arm is 5 moving in the direction to pull the thread and set the stitch, said means comprising a movable element on the rock-arm and an actuating device therefor on a stationary part of the machine, and means for throwing 10 said disk into ineffective position at a predetermined time during the pulling stroke of said rock-arm, said last mentioned means being adjustable so as to actuate said disk at different distances from said first mentioned actuating means for the disk, whereby the length of thread used in the respective stitches may be varied.

3. In a sewing machine, the combination with a stitch-forming mechanism, of a 20 thread-measuring and take-up device comprising an oscillatory arm, a thread-guide thereon, a curved flange located on said oscillatory arm in coöperative relation to said thread-guide, an eccentric disk pivotally mounted on said oscillatory arm and adapted to clamp the thread against the inner side of said curved flange, means for throwing 25 said eccentric disk into effective position when said oscillatory arm moves in the direction to pull the thread and set the stitch, and means for moving said cam into ineffective position at a predetermined time during the pulling stroke of said oscillatory arm.

35 4. In a sewing machine, the combination with a stitch-forming mechanism, of a thread-measuring and take-up device comprising an oscillatory arm, a thread-guide thereon, a member movably mounted on 40 said arm in coöperative relation to said thread-guide and adapted to clutch the thread therein, a lever arm pivotally mounted on said oscillatory arm and operatively connected to said movable member, a latch member 45 in the path of said lever arm adapted to actuate the same to positively move said movable member into effective position when said oscillatory arm moves in the direction to pull the thread and set the stitch, and a tripping device arranged to positively move said movable member into ineffective 50 position at a predetermined time during the pulling stroke of said oscillatory arm.

55 5. A thread-measuring and take-up device comprising an oscillatory arm having a curved flange thereon which is provided with thread-guides at its opposite ends, a cam pivotally mounted on said arm in coöperative relation to said flange and adapted to clutch the thread between the ends of 60 said flange, a lever-arm pivotally mounted on said oscillatory arm and operatively connected to said cam, means for actuating said lever-arm to throw said cam into effective

position when said oscillatory arm moves in the direction to pull the thread, and means for moving said cam into ineffective position at a predetermined time during the pulling stroke of said oscillatory arm.

6. A thread-measuring and take-up device comprising an oscillatory arm having a curved flange thereon which is provided with thread-guides at its opposite ends, a cam pivotally mounted on said arm in coöperative relation to said flange and adapted to clutch the thread between the ends of said flange, a lever-arm pivotally mounted on said oscillatory arm and operatively connected to said cam, a latch member mounted in the path of the free end of said lever-arm and adapted to actuate said lever-arm when the oscillatory arm moves in one direction, whereby said cam is moved into effective position, and a tripping device arranged in the path of a projection on said cam, whereby said cam is moved into ineffective position at a predetermined time during the stroke of the oscillatory arm.

7. A thread-measuring and take-up device comprising an oscillatory arm having a curved flange thereon which is provided with thread-guides at its opposite ends, a cam pivotally mounted on said oscillatory arm and operatively connected to said cam, an arcuate bracket arranged in coöperative relation to said oscillatory arm, a spring latch member mounted on said bracket in the path of the free end of said lever-arm and adapted to actuate said lever-arm when the oscillatory arm moves in one direction, whereby said cam is moved into effective position, and a member adjustably mounted on said bracket and having a projection arranged in the path of a projection on said cam, whereby said cam is moved into ineffective position at a predetermined time during the stroke of the oscillatory arm.

8. A thread-measuring and take-up device comprising an oscillatory arm having a thread-guide thereon, a clutch member pivotally mounted on said oscillatory arm in coöperative relation to said thread-guide and adapted to clutch the thread therein, an actuating member movably mounted on said oscillatory arm and operatively connected with said pivotal clutch member, a resilient latch member arranged to engage said actuating member when the oscillatory arm moves in one direction whereby the clutch member is moved to engage the thread in said thread-guide; an arcuate supporting bracket and a tripping device adjustably mounted on said arcuate supporting bracket so as to move said clutch member from the thread at a predetermined time.

9. A thread-measuring and take-up device comprising an oscillatory arm having a thread-guide thereon, a cam pivotally mounted on said oscillatory arm in coöperative re-

lation to said thread-guide and adapted to clutch the thread therein, an actuating member movably mounted on said oscillatory arm and operatively connected to said pivotal cam, an arcuate supporting bracket mounted adjacent to said oscillatory arm concentric with the pivot thereof, a resilient latch member arranged on said arcuate supporting bracket to engage said actuating member when said oscillatory arm moves in one direction whereby the cam is moved to engage the thread in said thread-guide, and a tripping device adjustably mounted on said arcuate supporting bracket with respect to

said latch member and adapted to engage 15 said cam and release the same from the thread in said thread-guide at different predetermined intervals during the stroke of said oscillatory arm.

In testimony whereof we have signed our 20 names to this specification in the presence of two subscribing witnesses.

GEORGE S. SAVIGNAC.
CHARLES E. MYERS.
